UNITED STATES PATENT OFFICE

MICHAEL J. MCRALE, OF SCRANTON, PENNSYLVANIA

FLYER CONSTRUCTION

Application filed October 17, 1930. Serial No. 489,401.

This invention relates to improvements in flyer block constructions and more particularly to improvements on the constructions shown in my prior application Serial Numbers 458,210, 458,211 and 458,212, filed May 31, 1930.

In these applications there was described a novel method and means for retaining flyer wires in flyer blocks. The improvements of the present invention are more particularly concerned with the incorporation of a novel flyer wire retaining means in a flyer block which is adapted for free rotation on a spindle tip of uniform diameter.

It is an object of this invention to provide an improved flyer block having an eccentric retaining flange and flyer wire retaining means.

It is another object of this invention to provide an improved flyer block with an eccentric retaining flange and an integral flyer wire retaining skirt.

Yet another object of this invention is the provision of an improved flyer block construction having a self locking foot and a wire retaining skirt together with locking means associated therewith.

It is also an object of this invention to provide an improved flyer block construction having a self locking foot and a wire support together with locking means for securing a wire to the support.

These and other desirable objects and advantages of the present invention will be illustrated in the accompanying drawings and described in the specification, certain preferred examples being shown by way of illustration only, for, since the underlying principles may be incorporated in other specific mechanical devices it is not intended to be limited to the ones here shown except as such limitations are clearly imposed by the appended claims.

In the drawings like numerals refer to similar parts throughout the several views,

of which Fig. 1 is a vertical section partly in elevation of an improved flyer block having integral wire retaining means;

Fig. 2 is a view similar to Fig. 1, showing a modified form of the block with upstanding skirt and locking nut;

Fig. 3 is a view similar to Figs. 1 and 2, showing a modification of the construction shown in Fig. 2, and

Fig. 4 is a bottom plan view of a block showing the self locking or retaining flange.

Referring now to the drawings, there is shown a conventional bobbin indicated generally by the numeral 1, and mounted on the usual spindle 2. The spindle 2 is usually slightly tapered to permit gripping engagement of the bobbin and is provided at its upper portion with a section 3 of uniform diameter adapted to receive a flyer block, designated generally by the numeral 4. The bobbins 1 are provided with end plates 5 secured thereto in any suitable manner as by means of screws, not shown. The end pieces are provided with the usual locking plates 6, secured in any desired manner as by means of screws, not shown, and adapted to retain the members 4 upon the shafts 3 when the blocks are inserted into the plates 6 and the spindles introduced through the bobbin with the upper tip 3 passing through the central apertures of the flyer blocks. It will be readily appreciated that the members 4 can be introduced into the member 6 by inserting the offset flanges or feet 7 into the aperture and then dropping the block therein. The introduction of the spindle into the bobbin and through the block, centers the latter and prevents its movement in such a manner as to slide out of the apertured plate 6.

Referring now to Fig. 1 the embodiment of the invention therein disclosed includes a body portion 10 having the usual central aperture 11 and a flange 12 of uniform diameter intermediate its length and integral therewith. Superjacent the flange 12 is a flange

13 of greater diameter, the two flanges forming a wire receiving groove or channel 14 therebetween adapted to receive a flyer wire, indicated generally at 15. The member 13 is provided with a depending flange 16 which, in turn, is formed with opposed slots 17 permitting the introduction and retention of the flyer wires 15, and serving to lock the latter in position. To insert a flyer wire into position the block may be removed from the spindle or not as desired, the wire being grasped between two of the fingers and introduced under the skirt 16, the thumb being placed on the opposite side of the block after which the arms of the wire are forced towards the thumb and slipped into the slots or grooves 17. As indicated in my prior applications, above identified, the slots 17 may be provided with wire retaining grooves of any desired configuration. It will thus be seen that the device shown in Fig. 1 may be readily attached to or removed from a spindle and its associated bobbin and, in addition, broken flyer wires may be readily removed and new ones replaced without disturbing the block or the spindle, and, that this repair or new installation may be done on the machine without requiring the removal of the blocks and the separate renewal of the wires. This construction obviates the necessity of maintaining complete duplicate sets of blocks to permit the removal of the blocks and their handling at a point separate from the machine, for the purpose of refitting with flyer wires. Owing to the relatively short life of the flyer wires, replacements, even under the most favorable circumstances, are required at least once every four to six weeks. The delays incident to the stoppage of spinning machines for the removal of flyer blocks and replacement with others is an appreciable item in manufacturing costs. With the present novel improvements, as has been set forth above, it is not necessary to remove the blocks from their spindles as the wires may be inserted or removed by a simple manual operation, without requiring the use of special tools or skilled labor. With the flyer blocks of the present invention in use any spinning machines operative can readily replace the flyer wires without waiting for the services of mechanics usually assigned to this task. This facility of insertion and removal increases the efficiency of both the machine and its operative while reducing labor costs, not only lowering the investment in replacement parts but also permitting a lower initial investment in flyer blocks due to their simplicity of construction. The flyer block just described is readily formed by simple machining operations and is susceptible of manufacture on automatic machines now available.

Referring now to Fig. 2 there is shown a modification of the construction shown in Fig. 1. In this construction a central flange

20 is provided with an upstanding skirt 21 and with the usual opposed wire engaging slots 22. The member 20 in connection with the skirt 21 forms a channel 23 which is adapted to receive a locking device such as a screw threaded nut 24 in threaded engagement with the upper threaded portion 25 of the body of the flyer. This construction permits the flyer wire 15 to be forced into engagement with the supporting platform 20 and be maintained thereagainst. The member 24 may be cut away internally as indicated at 26 to prevent cutting of the wires or body of the flyer.

While a lock nut of the screw threaded type has been shown it will of course be appreciated that any suitable locking means may be used, such as a bayonet joint construction, or other well known locking means familiar to those skilled in the art.

The use of a support with an upstanding slotted flange permits the insertion of the wire in place and the association of the locking means therewith without involving a rotation of the wire itself, which, under certain circumstances, might be a disadvantage.

The modified construction shown in Fig. 3 is similar to that shown in Fig. 2 with the exception that the platform support 30 is not provided with a skirted flange, and the locking member 31 is provided with a depending portion or skirt 32 and the opposed slots 33. As shown in the drawings this locking member is a lock nut having threads 34 engaging similar threads on the body of the flyer. A bayonet joint or other suitable locking means may be substituted for the screw thread means here shown without departing from the spirit of the invention. The bayonet joint permits the securing of the flyer wires in place and particularly where the latter are provided with raised portions or humps adapted to afford a spring tension against the retaining member. The use of a bayonet joint permits the securing of a locking effect by a fractional turn of the retaining member rather than requiring several complete turns as with a screw threaded assembly.

It will now be appreciated that there has been provided a plurality of flyer block constructions in which demountable flyer wires are adapted to be positioned and which are particularly suited for use with spindle tips of uniform diameter.

In accordance with the provisions of the patent statutes I have described the principles of operation of my invention, together with the device which I now consider to represent a preferred embodiment thereof; but I desire to have it understood that the devices shown are only illustrative of the basic concept of the present invention, and that the said invention may be carried out by other means.

What is claimed is:

1. A flyer including an apertured body having a uniform aperture diameter, an offset flange at the bottom of the body, and a skirted flanged flyer wire support having wire retaining means therein encircling the body and integral therewith.

2. A flyer including an apertured body having an offset flange at the bottom, and a skirted flanged flyer wire support having wire retaining means therein encircling the body and integral therewith.

3. A unitary flyer construction including a centrally apertured body, an offset flange at the bottom of the body, a uniform flange at the top of the body, a depending skirt on the said top flange, opposed slots in the skirt, and a second top flange subjacent the first top flange and forming a wire receiving groove therewith.

4. A flyer including an apertured body, an offset flange at the bottom of the body, a uniform flange superjacent the offset flange, an upstanding skirt on the upper flange, and opposed wire-engaging slots in said skirt.

5. A flyer including an apertured body, an offset flange at the bottom of the body, a uniform flange superjacent the offset flange and intermediate the body, an upstanding skirt on the upper flange, opposed wire-engaging slots in said skirt, and locking means engaging the body of the flyer and the skirted flange.

6. A flyer including an apertured body, an offset flange at the bottom of the body, a uniform flange superjacent the offset flange and intermediate the body, an upstanding skirt on the upper flange, opposed wire-engaging slots in said skirt, and screw-threaded locking means engaging the body of the flyer and the skirted flange.

7. A flyer including an apertured body having an offset flange at the bottom, an integral flanged support on the body, and locking means associated with the support, said locking means including a removable member having a depending skirt adapted to encircle the support and opposed slots in the skirt.

8. A flyer including an apertured body having an offset flange at the bottom, an integral flanged support on the body, and locking means associated with the support, said locking means including a screw-threaded removable member having a depending skirt adapted to encircle the support and opposed slots in the skirt.

9. A flyer including an apertured body having an offset flange, a flanged flyer wire support encircling the body and integral therewith, and means associated with said support adapted to retain a flyer wire in operative position in said flyer, said means including a removable member having a de-

pending skirt provided with opposed wire receiving slots.

10. A flyer block for spinning machines, including an apertured body, an eccentric foot on the body, a flanged and skirted flyer wire support encircling the body and cooperating therewith, and flyer wire locking means associated with said support, said locking means being adapted to engage ready formed flyer wires.

In testimony whereof I affix my signature.
MICHAEL J. McHALE.
